BENSON MAYO, OF CHATHAM, MASSACHUSETTS.

Letters Patent No. 71,081, dated November 19, 1867.

IMPROVED WINDOW-BLIND FASTENING.

The Schedule referred to in these Letters Patent and making part of the same.

TO ALL WHOM IT MAY CONCERN:

Be it known that I, BENSON MAYO, of Chatham, in the county of Barnstable, and State of Massachusetts, have invented a new and useful Improvement in Window-Blind Fastening; and I do hereby declare that the following is a full, clear, and exact description thereof, which will enable those skilled in the art to make and use the same, reference being had to the accompanying drawings, forming part of this specification, in which—

Figure 1 is a front outside view of a window having my improved fastening for the blind.

Figure 2 is a horizontal cross-section looking downwards, taken in the line x x , fig. 1.

Figure 3, a vertical section, taken in the line y y , fig. 2.

Similar letters of reference indicate corresponding parts.

This invention relates to an improved fastening for window-blinds, and consists in a device which catches and holds the blinds either open or closed alike, as hereinafter more particularly described.

On the bottom edge of each blind A is fastened a metal spur, a , projecting downwards, and on the sill B of the window-frame C is fastened a latch-spring, b , which catches the spur a when the blind is closed, to hold it in place. In front of the latch-spring b is placed a guard, c , to protect the end, and prevent it from catching against clothing. Bracket-rests d are fastened to the house on each side of the window-frame C , on each of which rests is fastened a latch-spring, b' , which catches the spur a , to hold the blind in place when opened, in the same manner that it is held by the spring b when closed. The bracket-rest d also supports the blind, and protects the spring b' , by preventing sagging of the blind.

Having described my invention, I claim as new, and desire to secure by Letters Patent—

The combination of the spur a , the latch-springs b b' , the guard c , the bracket-rest d , and the window-blind A , arranged and operating substantially as and for the purpose herein described.

BENSON MAYO.
